[57] CLAIM

The ornamental design for a handle, as shown and described.

DESCRIPTION

FIG. 1 is a front perspective view of a handle showing my new design.

FIG. 2 is a rear elevational view thereof.

FIG. 3 is a side elevational view taken from the right of FIG. 1, the side opposite being a mirror image thereof.

FIG. 4 is a front elevational view thereof.

The underside of the handle is flat and unornamented.

FIG. 1

FIG. 2

FIG. 4

FIG. 3
